UNITED STATES PATENT OFFICE.

CARL O. LIEN, OF SUTTON, NORTH DAKOTA.

GAS-ENGINE STARTER.

1,121,738.

Specification of Letters Patent. Patented Dec. 22, 1914.

Application filed February 4, 1914. Serial No. 816,610.

To all whom it may concern:

Be it known that I, CARL O. LIEN, a citizen of the United States, residing at Sutton, in the county of Griggs and State of North Dakota, have invented certain new and useful Improvements in Gas-Engine Starters, of which the following is a specification, reference being had to the accompanying drawings.

10 This invention relates to new and useful improvements in engine starters, and more particularly to a gas engine starter, and the primary object of the invention is to provide a device of this character applicable 15 to the intake pipe of a gasoline engine, whereby to admit heated gases to the latter at times when the same is extremely cold and difficult to start.

A further object of the invention resides 20 in providing a device which is simple and durable in construction, inexpensive to manufacture, and one which will be very efficient and useful in operation.

With these and other objects in view, the 25 invention consists in the novel features of construction, combination and arrangement of parts as will be hereinafter fully described and claimed.

In the accompanying drawings forming 30 a part of this application, Figure 1 is an elevation partly in section of a device constructed in accordance with my invention, as shown applied to use; and Fig. 2 is an elevation of a slightly modified form of 35 the invention.

In describing my invention, I shall refer to the drawings in which similar reference characters designate corresponding parts throughout the several views and in which—

40 1 indicates diagrammatically and in dotted lines an internal combustion engine of the usual or any preferred type, I have shown one of the four cylinder type, to which is connected the intake pipe 2, leading from a carbureter 3.

45 It is a well known fact that when a gas engine becomes extremely cold, such as it will do in certain periods of the year when left standing for any length of time, it is a 50 very difficult matter to start it. This is due particularly to the fact that the gasoline will not evaporate well in the cylinders when the latter are extremely cold and my invention contemplates the provision of a means 55 whereby warm air and gas may be drawn into the cylinders under such conditions,

thus making it an easy matter to start an engine under such conditions.

It must be here stated that the device is applicable to gas engines, applied to automobiles or traction engines, but particularly the latter, where it is necessary to retain the same in the open air for long periods at a time.

In carrying out my invention, I provide a 65 housing or body 4, having a spout-like projection 5 formed thereon which is connected to the intake pipe 2, at any desired point thereon. This housing or body 4 is provided with a filling opening, in which is 70 mounted a plug 6, and a manually operable valve 7 is arranged in the projection 5, whereby to admit gases to generate in the body or housing 4 and enter the intake pipe. A drip cock 8 is also provided in one side of 75 the body or housing 4 to determine the right amount of gasoline in the member 4. This body 4 is filled with gasoline to the level of the drip cock and the object is to heat the gasoline so as to form a gas and admit the 80 gas through the medium of the valve 7 to the intake pipe and on to the cylinders. A support 9 is, therefore, provided, suspended from the lower portion of the body 4, for carrying a burner 10. This burner may be 85 readily lighted, it will be seen, so as to heat the contents of the body 4 and a shield 11 is provided in connection with the support to entirely encircle the burner and turn the heat against the housing or body 4 and, at 90 the same time, shield the burner from wind.

In the operation of the device, after the body 4 has been filled to the desired degree with the gasoline, the burner is lighted and the valve 7 opened. Within a short while the 95 gasoline will be heated and rise, in the form of a gas, in the member 4 and pass out through the valve 7 to the intake pipe, where it is conducted to the cylinders. These heated gases are readily ignited and by 100 cranking the engine slightly, there will be no difficulty in starting. After the engine once starts, the gas will be properly drawn from the carbureter and the burner may be extinguished and the valve 7 closed. Should 105 the pressure of the gases in the member 4 become excessive they may readily find an exit through the medium of a spring held safety valve 12 provided in the top of the body or housing 4.

In Fig. 2, I have shown a slightly modified form of the invention, wherein to an in-

take pipe 13, an extension 14 of a hollow body or housing 15, is connected. This connection and body is substantially the same as the connection and the body described in the first mentioned form, but in this form, the 5 manually operated valve is omitted. The body is provided with a filling plug 16 and a drip cock 17. This body may be filled with gasolene to the desired level, and in 10 order to cause a gas to be formed in the body 16, a burner, such as a blow torch 18 is provided. This blow torch may be readily applied to the body or housing 15 and as the 15 gases are formed in said body the same may readily pass to the intake pipe and on to the cylinders of the engine. It will be seen that this form of the device is considerably simpler than the form first described, but is substantially the same so far as the forming 20 of the gases and the conducting of the same to the cylinders, is concerned.

From the foregoing it will be seen that I have provided a simple, inexpensive and efficient means for carrying out the objects 25 of the invention and while I have particularly described the elements best adapted to perform the functions set forth, it is obvious

that various changes in form, proportion and in the minor details of construction may be resorted to without departing from the 30 spirit or sacrificing any of the principles of the invention.

Having thus described this invention, what I claim is:—

In a device of the class described, the combination with an intake pipe of a gasolene engine; of a hollow body having a tubular lateral projection formed thereon engaged with said intake pipe, a manually operated valve arranged in the projection of the body, 35 means formed in connection with the body whereby the latter may be filled with liquid contents, a drip cock mounted in the side of the body, means for heating the contents of the body whereby to form a gas to be conducted to the intake pipe, and a safety valve mounted in the top of said body.

In testimony whereof I hereunto affix my signature in the presence of two witnesses.

CARL O. LIEN.
